MARKER OR CLIP.

1,103,031.

Specification of Letters Patent. Patented July 14, 1914.

Application filed June 20, 1913. Serial No. 774,920.

To all whom it may concern:

Be it known that I, CHAPEL S. CARTER, a citizen of the United States, residing in Ansonia, in the county of New Haven and 5 State of Connecticut, have invented certain new and useful Improvements in Markers or Clips, of which the following is a full, clear, and exact description.

This invention relates to markers or clips 10 for use in card indexes and for other purposes, and more particularly to a marker or signal in the form of a detachable metal clip provided with an opening adapted to expose and indicate any of a plurality of numbers 15 or other characters arranged along the upper margin of a card, and further provided with a portion adapted to extend upward from the top edge of the card and serving the double function of a visible signal and 20 a tab or finger piece.

The primary object of the invention is to provide a marker or clip of the type indicated, wherein the upwardly projecting tab or signal portion and the body portion having the sight opening for the numbers or characters on the card, are combined in a simple and novel way with each other and with means for securing the clip or marker firmly on the marginal portion of the card. 25

It is also aimed to provide a marker or clip which can be easily applied to and removed from the card, which can be easily and cheaply manufactured, and which has still further advantages hereinafter pointed out.

To these and other ends, the invention consists in the novel features and combinations of parts to be hereinafter described and claimed.

In the accompanying drawing, Figure 1 40 is a front elevation of an index card showing two markers or clips embodying my improvements, one of the same being fully applied to the margin of the card and the other being only partially applied, Fig. 2 is 45 an enlarged front elevation of the marker or clip shown at the left of Fig. 1, Fig. 3 is a section on line 3—3 of Fig. 2, and Fig. 4 is a plan view of the blank from which the marker or clip is constructed.

Referring to Fig. 1, 5 indicates the upper portion of a record or index card and 6 indicates a row or series of numbers or other characters extending lengthwise along the upper margin of the card, as usual in devices of this character.

7 and 8 indicate markers or clips embodying my improvements, which markers or clips are adapted to straddle the upper edge of the card and expose and direct attention to any of the series of numbers or characters 60 on the card as may be desired. The marker or clip 7 is illustrated in detail in Figs. 2, 3 and 4. It is formed by taking a flat elongated plate 9 of sheet metal (Fig. 4), cutting through the same near one end to present the outline of a tab 10 and cutting through the blank near the middle to form a tongue 11, and then bending the blank into the shape illustrated in Figs. 2 and 3. The blank is bent about a transverse axis adjacent the base or uncut portion of the tab 10 which tab remains in its original condition as the metal around it is bent substantially into contact with the other end portion of the blank. This provides a clip or marker 65 formed of a sheet of metal doubled on itself to present two legs or branches 12, 13, one of which (12) is provided with a tab or signal portion 10 extending upward from the junction of said legs or branches, while the 70 other leg or branch 13 is provided with an opening 14. The tongue 11 in the leg 12 is located immediately back of the opening 14 and it projects forward out of the plane of the leg 12, as shown in Fig. 3, so as to press tightly against the face of a card straddled by the legs 12, 13. The tongue 11 extends upwardly at such an angle that it does not interfere with the placing of the clip in position on the edge of the card, and yet when 75 the clip has once been properly located, the tongue will hold it firmly in position by exerting pressure on that portion of the card at the rear of the opening 14. The advantage of locating the tongue 11 back of, and in line with, the opening 14 is that said tongue 11 in acting on the flexible body of the card will push the paper forward in the opening to such an extent as to produce an effective interlocking of the clip with the paper at the inner edge of the opening. The active portion of the tongue 11 is located 80 wholly within the opening 14.

The application of the marker or clip to the edge of the card is facilitated by bending or turning up slightly one of the lower corners of the front leg or member 13. It is preferred to turn up the lower right hand corner of the leg or member 13, as indicated 85 at 15 in Fig. 2.

The marker or clip 8 shown at the right of Fig. 1, is of somewhat modified construction as compared to the marker or clip 7 which has just been described. The clip 7 has an 5 imperforate tab portion 10 which may be coated with enamel of any desired color. The tab portion 10^a of the clip 8 on the other hand, is plain *i. e.* uncoated, and the tab portion is furthermore provided with an 10 opening or perforation 10^b. It is understood, of course, that in a card index it is desirable that different groups or series of markers be suitably distinguished from each 15 other for classification purposes, and it is for this reason that the projecting tab portions which are visible at all times, are distinguished by color or otherwise. In the case illustrated, the perforation 10^b of the 20 clip 8 is intended to permit the suspension of the card by means of the clip when such is desired, but the perforations of the tab portions of a number of clips may serve only 25 for the purpose of distinguishing such clips from those of another group or series.

25 My improved markers or clips are applied to the card in the manner shown in Fig. 1. The clip is held at an angle to the card, as shown to the right of Fig. 1, while the legs or members 12, 13, are set over the 30 edge of the card at the point 15 where the edge of the member 13 is slightly upturned. The upturned corner permits the edge of the card to be readily introduced between the legs or members of the clip, and the latter may then be readily forced into its ultimate position while turning the axis of the 35 clip into a vertical position. The clip 7 in Fig. 1 is shown in its finally seated position on the edge of the card with the number 10 40 on the card exposed through the opening 14. Of course, the clip may be readily slid along the edge of the card to expose and call attention to another number of the series when such is desired.

45 The rear leg or member 12 of the clip is preferably somewhat longer than the front member 13, as shown, so as to guide the edge of the card more effectively into the space between the legs or members. The lower 50 edge of the front member 13 is substantially in contact with the rear member 12 and is only upturned or flared at the corner for the insertion of a card, or similar article, between it and the other leg while the legs are 55 in contact with each other so that a card will readily ride over the lower edge of the front member when the card is in its ordinary vertical position. The lower extremity of the

flare of the upturned corner begins at a point above the lowest edge of its leg, as 60 shown more particularly in Fig. 2.

Without limiting myself to the precise construction shown I claim:

1. A marker or signal for card indexes comprising a metal plate having integral 65 tongues struck out of the same, and pointing in the same general direction, one of said tongues being wider than the other, the metal around the wide tongue being bent back or folded over relative to the main portion of the plate, whereby said tongue serves as a tab, the bent over portion of metal struck from around said tab being in close proximity to the main body portion of the plate at the same side of the plate as the 70 narrow tongue, and having its opening in line with the narrow tongue, whereby the latter may act as a gripping member, the active portion of such gripping member being located wholly within said opening, so 75 as to press the card, or other article, into contact with the edges of said opening; substantially as described.

2. A marker or clip comprising a metal plate doubled on itself to present a front leg 85 and a rear leg, one of said legs having its lower edge normally in substantial contact with the face of the other leg substantially throughout the length of such lower edge, and said first named leg having an upturned or flared corner at its lower part located above the lowermost extremity of said leg, said flared corner being spaced from the 90 opposing face of the other leg so that a card, or the like, may be interposed between the 95 normally contacting portions of the legs; substantially as described.

3. A marker or clip, comprising a metal plate doubled on itself to present two legs or members, the front leg having the lower 100 edge or extremity thereof normally in substantial contact with the rear leg, above the lower edge of such rear leg, said front leg having an upturned or flared portion at a 105 lower corner thereof, and the lower edge of said front leg being extended downward beyond the upturned or flared corner so that a card or the like will ride over the front leg without catching in such upturned or flared corner; substantially as described.

In witness whereof, I have hereunto set my hand on the 18th day of June 1913.
